UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

WORK-HOLDING MEANS FOR GRINDING-MACHINES, LATHES, AND LIKE MACHINE-TOOLS.

1,100,265.

Specification of Letters Patent. Patented June 16, 1914.

Application filed June 12, 1913. Serial No. 773,179.

To all whom it may concern:

Be it known that I, ARTHUR W. SMITH, citizen of the United States, and resident of the borough of Manhattan, city of New

5 York, in the county of New York and State of New York, have invented certain new and useful Improvements in Work-Holding Means for Grinding-Machines, Lathes, and like Machine-Tools, of which the following 10 is a specification.

My invention relates to grinding machines, lathes and like machine tools and is directed more particularly to work holding means for such machines. Heretofore 15 in grinding platens for typewriting machines it has been customary to provide separate work holding means or devices for platens equipped with distinctively different kinds of platen heads, line spacing 20 wheels, etc.

One of the main objects of my present invention is to overcome the above mentioned disadvantages and to provide work holding means which are comparatively simple in 25 construction, efficient in use, and which are adapted to coöperate with work of distinctively different character, or with platens, for example, equipped with fittings having distinctly different characteristics.

30 To the above and other ends which will hereinafter appear, my invention consists in the features of construction, combinations of devices and arrangements of parts set forth in the following description and particularly pointed out in the appended claims.

In the accompanying drawings wherein like reference characters indicate corresponding parts in the various views, Figure 1 is a fragmentary front elevation with 40 parts in section of one form of machine tool embodying my invention.

Figs. 2 to 7, inclusive, are detail fragmentary side views of typewriter platens with different forms of equipment or fittings 45 with which the work holding devices of the present invention are adapted to co-operate. Fig. 8 is a fragmentary sectional view showing a portion of one of the work holding devices. Fig. 9 is a detail end view 50 showing one of the working holding devices mounted in place on its work supporting member. Fig. 10 is a detail longitudinal sectional view of one of the detachable centers, the section being taken on the line

x—x of Fig. 11 and looking in the direction 55 of the arrow at said line. Fig. 11 is an end view of the same looking in the direction of the arrow in Fig. 10.

In order to more readily arrive at an understanding of the present invention and 60 the character of work that it was devised more especially to accomplish, I have illustrated several platens for typewriting machines equipped with different characters of platen heads or fittings. These represent 65 but comparatively few of the many differentially equipped platens that the work holding means of the present invention are adapted to co-act with to properly hold them in place and effect a rotation thereof 70 in the grinding machine, though the platens illustrated will suffice to show the application of the invention under various conditions.

The body portion of each platen is represented 75 by the reference numeral 1 although it will be understood that the diameters and lengths of these platens in different machines vary considerably as well as the platen heads, line spacing wheels, etc., 80 mounted thereon. The body portion 1 of each platen has two heads secured thereto; one head, designated as a whole by the reference numeral 2, being secured at one end of the platen, whereas the other head, 85 designated as a whole by the reference numeral 3, is secured to the other end of the platen. These platen heads vary considerably 90 in construction in different machines. One may have a comparatively long hollow sleeve or hub 4 projecting therefrom, as shown in Fig. 2, whereas another may have a relatively long trunnion or solid spindle 5 projecting therefrom, as shown in Fig. 2. In other instances the platen heads 2 may 95 have different forms of hubs 4^a, 4^b, as shown in Figs. 3 and 4 respectively. Another form of platen head may not have a hub or projection but may have a central bearing opening 6 or 6^a therein as shown in Figs. 100 3 and 5 respectively. Then again some platen heads may be formed with crown teeth 7 to provide a line spacing wheel, as shown in Fig. 4. In other cases the line spacing teeth may be peripheral teeth, as 105 shown at 8 in Figs. 5, 6 and 7. In some instances, instead of the line spacing wheels being formed on the platen heads they may

be otherwise connected with the platens and a head at one end of each of such platens is formed with an off-set aperture 9, as indicated in Figs. 2 and 3. In still other instances the platen head at one end of each platen is provided with a finger wheel 10, as shown in Fig. 4. The solid spindles or trunnions corresponding to the trunnions 5 also vary widely on different platens as will be seen from an inspection of the trunnions 11 and 12 as shown in Figs. 6 and 7 respectively. As hereinbefore indicated these represent but a comparatively few of the different styles of equipment on platens 15 employed in different machines, and it should also be understood that the number of teeth on different line spacing wheels vary even in the same character of constructions. By the present invention I provide 20 work holding means with the aid of which any one of these, and many other different styles and sizes of platens, may be readily connected to their driving means and properly positioned and centered in the grinding 25 machine by which the surfaces of the platens may be ground. The means by which this is accomplished are shown in Fig. 1 mounted in a conventionally represented grinding machine or lathe, only so 30 much of said machine being shown as is necessary to an understanding of the invention in its embodiment therein. It will be understood that, so far as my present invention is concerned, any suitable grinding 35 machine, lathe or machine tool may be employed, the novel devices of the present invention relating more particularly to work holding means.

The bed 13 of the machine in the present 40 instance supports the usual head and tail stocks 14 and 15 respectively. The live spindle is driven by a pulley 16 and receives at the inner end thereof what I term a working supporting member 17 having a 45 tapered end 18 for the reception in a corresponding opening in the inner end of the live spindle. The inner end of the work supporting member 17 is apertured to receive the tapering end 19 of a center 20. 50 The working or engaging face 21 of this center is tapering for reception in the center openings of the hubs 4, 4^a or 4^b, or in the center openings 6^a of the platen heads 2, the tapering of the center 20 enabling it to 55 co-act with platen heads having different size central openings. The work supporting member 17 is provided with an eccentric bearing portion 22 surrounded by a sleeve 23 which constitutes a part of a work 60 engaging member. Projecting inwardly from the edge of the sleeve, at one side thereof, is an extension 24 which is apertured in its end to receive the tapering portion 25 of an engaging pin 26, the pin projecting inwardly 65 beyond the inner end of the extension 24.

The inner end of the extension 24 is also provided with an inwardly extending engaging tooth, pin or projection designated as a whole by the reference numeral 27. This tooth has an upwardly extending flat 70 face 28 the plane of which is radial with the center of the sleeve 23. The top of the tooth is beveled as indicated at 29 and is formed with an inclined face 30, so as to present a sharp working edge 31 and a sharp 75 crown 32 parallel with the axial center of the spindles, and is also formed with a sharp crown 32, the edge of which is at right angles to the axial center of the sleeve 23. The purpose of this is to provide engaging means adapted to coöperate with the crown line spacing ratchet teeth 7, or the peripheral line spacing teeth 8 on the platen heads 2 with equal facility. In the event of the tooth engaging the crown ratchet 80 teeth an endwise engagement is effected between the crown 32 of the engaging tooth and the teeth 7 of the ratchet wheel, whereas an engagement may be effected between the edge 31 of the tooth 27 and the peripheral 85 ratchet teeth 8. This engagement provides an unlocking engagement between the engaging member and the platen head so as to connect and hold the platen for rotative movement with the live spindle. 90

In the event of the platen head 2 being provided with off-set apertures 9 therein, and not having line spacing ratchet teeth formed thereon, then the engaging pin 26 will be used to effect an interlocking engagement between the platen head and the work engaging member, it being understood that the pin 26 is seated in an aperture 9 of the platen head 2. It will be understood, moreover, that when the engaging pin 26 is employed the tooth 27 will not be effective to coöperate with the platen head, whereas when the tooth 27 is used the pin 26 is removed to afford an engagement between the tooth 27 and the teeth of the line 100 spacing ratchet wheel. 105

The sleeve 23 is fixed in position on the eccentric bearing member 22 by a set screw 33 which is received in a tapped opening in the sleeve and bears at its inner end against the surface of the eccentric. A loosening of the screw enables the sleeve to be turned on the eccentric or to be moved longitudinally thereof and the set screw is effective to hold the sleeve against displacement from the position to which it has been adjusted. It will be understood that a rotative adjustment of the engaging member on the eccentric 22 is effective to move the tooth 27 and engaging pin 26 nearer to or farther from the lathe center indicated by the dotted line *a* in Fig. 1. From an inspection of Fig. 9 this adjustment of the engaging devices toward and from the axial line of the lathe centers will be readily understood. This 115 120 125 130

rotative adjustment enables the engaging devices to be properly adjusted to co-act with different portions of the platen heads 2 in the manner hereinbefore indicated and 5 to afford a setting of such devices for platens of different diameters. The longitudinal adjustment of the sleeve enables an effective engagement between the engaging devices 27 and 26 and the platen heads 10 to be brought about, and to compensate for the differences in the construction of the platen heads 2 where, for example, they are provided with hollow spindles or hubs 4, 4^a, 4^b, or the platen heads have no such 15 hubs and are merely provided with central bearing openings 6^a. In the event of the platen heads 2 having solid spindles 34 or 35, as indicated in Figs. 6 and 7, the center 20 will be removed and the spindle 34 or 20 35 will be seated directly in the bearing opening which receives the taper 19 of the center 20, or in the extension of such opening. In all of the instances shown the platen heads 2 are coöperative with the 25 work holding devices carried by the live spindle, whereas the platen heads 3 are coöperative with work holding or supporting devices which are carried by the tail stock 15. These devices comprise a supporting member 36 tapered for reception in 30 the inner apertured end of the dead spindle. An annular opening or ball channel 37 is formed at the inner end of the supporting member 36, the vertically disposed face of 35 such channel receiving the horizontal thrust of a circular series of anti-friction balls 38. The inner annular wall of the channel receives the lateral thrust of the series of balls. A center-carrying member 39 is in 40 the nature of a hollow spindle which is received in and extends through to the outer end of the supporting member 36. The inner end portion of this center carrying member is formed with a cone 40 which 45 bears against the circular series of anti-friction balls 38. A cylindrical dust guard or shield 41 is connected to the supporting member 36 and overlaps the joint between the cone 40 and the inner end of the supporting member 36 in order to exclude dust or grit from the ball bearings. The outer 50 end portion of the hollow center-carrier is internally threaded to receive the threaded portion 42 of a screw having an enlarged head 43. The under side of the head forms one wall of a bearing for a circularly arranged series of bearing balls 44, whereas a circumferential shoulder 45 on the screw forms another bearing wall for the balls 55 44. The series of balls 44 also receives a bearing on the inclined face 46 at the inner end of the supporting member 36. If desired a sleeve 47 may be connected to the head 43 of the screw and extend inwardly 60 to inclose the circular series of balls 44 in

order to exclude grit or dust from the bearings. A set screw 48 is received in a tapped opening in the center-carrier 39 and bears at its inner end against the unthreaded portion 49 of the screw to retain it in the 70 position to which it may be adjusted to regulate the pressure of the bearings against the balls, it being understood that the screw is effective to take up any lost motion and to compensate for any wear on the bearings. 75 The set screw 48 may be introduced into its tapped opening through an aperture 50 provided with the supporting member 36. The inner end of the center-support or carrier 36 has a tapering opening to receive 80 the tapered or conical end 51 of a center 52 provided with a tapering work engaging portion 53 which is angular in cross section, the center being shown rectangular in cross section in the present instance. In some instances this center may be replaced by a hollow center designated as a whole by the reference numeral 54, and shown in detail in Figs. 10 and 11. This center has a hollow tapering portion 55 and an internally 85 tapering serrated face 56 to engage various characters of spindles or hubs such as the spindles 5, 11 and 12, or the hub 57 on the platen heads 3. When the platen heads 3 are provided with central openings, such as 90 that indicated at 6 in Fig. 3 or at 58 in Fig. 4, the center 52 may be employed. It may also be used to coöperate with hollow spindles or hubs, such as the hub 57 in Fig. 5. It is believed that it will be unnecessary 95 to indicate more specifically just how these work holding means co-act with the spindles, hubs or centrally apertured platen heads since it is believed that it will be apparent to those skilled in the art from what 100 has been described. 105

From the foregoing description it will be understood that the work supporting or engaging means carried by the tail stock 15 are mounted on ball bearings to support the 110 platen for rotative movement with the live spindle of the grinding machine and that the off-set work engaging means 26, 27 are effective to engage the platen, or a part carried thereby, to fixedly connect the work or platen to the live spindle in order to rotate the platen therewith.

The work holding means shown and described are effective to coöperate with many different styles of platens and the construction of the parts is such that they may be readily adjusted, regulated or set to co-act with the different size platens. 115

While I have shown and described my invention embodied in a grinding machine or lathe, and while the invention was designed more especially for use in such machines and for more effectively holding typewriter platens therein, it should be understood that the work holding devices of my 125 130 invention may be used in other types of work holding devices.

invention have a wide range of use and that I do not limit myself to their embodiment in any particular character of machine tool, and that the invention may be employed for various kinds of work.

What I claim as new and desire to secure by Letters Patent, is:—

1. Work holding means for grinding machines lathes and like machine tools comprising a rotative supporting member having an eccentric bearing portion, and a work engaging member adjustably mounted on the eccentric bearing portion of said supporting member.
2. Work holding means for grinding machines lathes and like machine tools comprising a rotative supporting member having an eccentric bearing portion, a work engaging member mounted on the eccentric bearing portion of said supporting member, and means for affording an adjustment of said work engaging member on said eccentric portion both rotatively and axially of said supporting member.
3. Work holding means for grinding machines lathes and like machine tools comprising a rotative supporting member having an eccentric bearing portion, a work engaging member adjustably mounted on the eccentric bearing portion of said supporting member, and a work engaging projection carried by said work engaging member.
4. Work holding means for grinding machines lathes and like machine tools comprising a rotative supporting member having an eccentric bearing portion, and a work engaging member adjustably mounted on the eccentric bearing portion of said supporting member, said work engaging member having a work engaging tooth projecting therefrom and adapted to effect a sidewise or endwise engagement with the work.
5. Work holding means for grinding machines lathes and like machine tools comprising a rotative supporting member having an eccentric bearing portion, a work engaging member adjustably mounted on the eccentric bearing portion of said supporting member, and a center carried by said supporting member and having a conical work engaging face.
6. Work holding means for grinding machines lathes and like machine tools com-

prising a rotative supporting member having an eccentric bearing portion, a work engaging member adjustably mounted on the eccentric bearing portion of said supporting member, and a center carried by and detachable from said work supporting member.

7. Work holding means for grinding machines lathes and like machine tools comprising a rotative supporting member having an eccentric bearing portion, a work engaging member mounted on the eccentric bearing portion of said supporting member, means for affording an adjustment of said work engaging member on said eccentric portion both rotatively and axially of said supporting member, said engaging member having a work engaging tooth projecting therefrom, a work engaging pin carried by and detachable from said work engaging member, and a center carried by and detachable from said supporting member, said center having a conical work engaging face.

8. Work holding means for grinding machines lathes and like machine tools comprising a supporting member adapted to be detachably connected with the live spindle of the machine and having a bearing portion eccentric to the axial line of the centers, and a work engaging member mounted and rotatively adjustable on said eccentric bearing portion, said work engaging member having an engaging device at one side of the axial center thereof, so that a rotative adjustment of the work engaging member on the eccentric bearing portion is effective to adjust said engaging device nearer to or farther from the axial line of the centers.

9. Work holding means for grinding machines lathes and like machine tools comprising a tooth beveled in two directions to engage crown or peripheral ratchet teeth on the work to be held, and means for affording an adjustment of said tooth toward and away from the axial line of the centers as well as parallel therewith.

Signed at the borough of Manhattan, city of New York, in the county of New York, and State of New York, this 11th day of June, A. D. 1913.
